UNITED STATES PATENT OFFICE.

JOSEPH W. McCANN, OF WASHINGTON, DISTRICT OF COLUMBIA.

DUMMY KEYBOARD.

No. 823,888.

Specification of Letters Patent.

Patented June 19, 1906.

Application filed July 27, 1905. Serial No. 271,522.

To all whom it may concern:

Be it known that I, JOSEPH W. McCANN, a citizen of the United States, residing at Washington, in the District of Columbia, have invented new and useful Improvements in Dummy Keyboards, of which the following is a specification.

My invention pertains to dummy or practice keyboards, and it contemplates the provision of a simple and durable keyboard calculated to enable a person of average intelligence with a reasonable amount of study and practice to acquire the quick and light touch necessary to bring down a matrix in the Mergenthaler linotype-machine at present in general use, to determine the speed he is making, to practice to the same advantage as on the keyboard of a Mergenthaler machine with a view of becoming proficient in the use of all of his fingers and thumbs in rapidly operating a Mergenthaler machine, and to memorize or fix in his mind the relative arrangement of the keys comprised in the keyboard of said machine, so that he can operate the keys speedily and correctly without looking at the keyboard.

Other advantageous features of the invention will be fully understood from the following description and claims when taken in connection with the accompanying drawings, forming part of this specification, in which—

Figure 1 is a perspective view illustrating the dummy keyboard constituting the present and preferred embodiment of my invention as the same appears when set up ready for use. Fig. 2 is a transverse section of the keyboard, and Fig. 3 is an enlarged perspective view illustrating one of the keys as removed and also illustrating the peculiar and advantageous manner in which the character-bearing label is applied to the key-body.

Similar letters designate corresponding parts in all of the views of the drawings, referring to which—

A is the body of the dummy keyboard. The said body preferably comprises a major portion *a*, of wood, and a layer of tin *b*, fixed on the upper side of the wood portion, and it is designed to be supported by a hinged prop *c* in such a position that its upper surface forms an inclined plane, as illustrated. When the keyboard is not in use, the prop *c* is folded against the back of the body *A*, so as to take

up but a minimum amount of space in storage 55 or shipment.

B is a copy-holder. This copy-holder preferably comprises a piece of sheet metal *d*, having a flange *e* at its lower edge, and a metallic frame *f* secured to the back of the sheet metal *d* and terminating in studs *g*, only one of which is illustrated, designed to be removably arranged in eyes *h* on the upper edge of the body *A*, Fig. 2. By virtue of this construction the copy-holder *B* may obviously be detached and laid flat against the under side of the body *A* for convenience in storage or shipment.

C is a space-bar, which is preferably of wood and is connected by strips *k*, of spring metal, with the upper edge of the body *A*, whereby it is normally retained in the position illustrated and yet is free to move down and up. At its left-hand end the space-bar is provided with a finger-piece *l*, preferably of spring metal, on the under side of which is fixed a dog *m*, arranged when the finger-piece is depressed to engage a toothed wheel *n*, carrying an arm *p*. The toothed wheel is designed to be rotated step by step by depression of the finger-piece *l*, and is held against retrograde movement by a gravitating pawl *r*. When the toothed wheel *n* makes a complete revolution, its arm *p*, acting against a pendent hammer *s*, forces said hammer against a bell *t*, and thereby apprises the student of the fact that he is approaching the end of a line.

The mechanism just described is preferably arranged to notify the student when he has set a line of ordinary newspaper measure averaging seven words or approximately twenty-seven ems, and when it is employed in connection with a number of, say, one hundred quads or other articles it enables the student to determine the speed he is making. In this use the operator places at his right on a suitable support one hundred quads. When the bell rings, he knows that he has set six words, and he then sets an additional word and picks a quad from the pile. This picking of a quad is a substitute for raising the lever of an ordinary Mergenthaler machine, and by observing a timepiece the student is enabled to readily determine the length of time it takes him to set one hundred lines or about twenty-seven hundred ems.

D D are the keys of the dummy keyboard.

These keys are relatively arranged in the same manner as the keys in the keyboard of the Mergenthaler linotype-machine and bear corresponding characters, and hence it will be apparent that a person practicing on the dummy keyboard will become acquainted with the Mergenthaler linotype-keyboard to such an extent that he can operate said keyboard with the fingers and thumbs of both hands accurately and speedily and this without looking at the keyboard. This latter is an important desideratum, inasmuch as it is advantageous for a Mergenthaler operator while operating the keyboard to watch the working of the machine. The keys D are grouped or relatively arranged on the inclined plane of the body A in the manner shown and are identical, with the exception that each bears a different character. For this latter reason a detailed description of the key shown in Fig. 3 will suffice to impart a definite understanding of all. The said key, Fig. 3, comprises a body u, of thin brass or other suitable spring metal, and a character-bearing label v, of paper or other flexible material. The key-body u has an inner bent end w, which is brazed or otherwise fixed to the inclined plane of the body A so that the major portion of the key-body rests horizontally at an acute angle to said inclined plane, Fig. 2, and it is also provided, adjacent to its free end with a shoulder x. This shoulder enables the maker to readily square the end of the label v, which is looped and connected in such form by adhesive or other means to the key-body, and in that way facilitates the proper application of the label.

It will be readily apparent from the foregoing that the keys D, connected to the inclined plane of the body A in the manner described, will give to the touch of an operator and when relieved of pressure will spring of themselves back to the normal position illustrated, also that the touch necessary to depress the free ends of the keys D is similar to that required to manipulate a key of the Mergenthaler-keyboard, and thereby bring down a single matrix. From this latter it follows that the student using my novel dummy keyboard is enabled to acquire not only speed, but also the proper touch so requisite to the successful operation of the Mergenthaler linotype-machine.

It will be gathered from the foregoing that my novel device is simple and well adapted to withstand the usage to which such devices are ordinarily subjected, also that the device will enable a student operator to attain a degree of finish and speed in practice-work which would require a much longer period to reach were the practice confined solely to the daily work on a machine when accuracy for-

bids an attempt at speed, and the necessity of sending up so many lines per minute makes it inexpedient to experiment on method.

65

In addition to the practical advantages which I have hereinbefore ascribed to my novel dummy keyboard it will be noted that the same is very light in weight and is therefore adapted to be carried from place to place with facility.

Having described my invention, what I claim, and desire to secure by Letters Patent, is—

1. A dummy keyboard comprising a body, 75 keys, of spring metal, fixed at one end to the body, a space-bar having a finger-piece at one end and a dog on said finger-piece, spring-metal strips connecting the space-bar and the body, a toothed wheel arranged to be rotated 80 in one direction by the dog, means for preventing retrograde movement of the toothed wheel, a bell carried by the body, and means operated by the toothed wheel for striking the bell when the wheel is turned through a 85 complete revolution.

2. A dummy keyboard comprising a body, 90 keys, of spring metal, fixed at one end to the body, a space-bar, a spring connection between the bar and the body, a bell, and means operated by the space-bar for ringing the bell when said bar is depressed a predetermined number of times.

3. A dummy keyboard comprising a body having an upper surface which forms an inclined plane, and keys, of spring metal, fixed at their inner ends directly to the inclined plane of the body and resting above and at an acute angle thereto.

4. A dummy keyboard comprising a body 100 having an upper surface arranged to form an inclined plane, and keys, of spring metal, having inner, bent ends brazed to the inclined plane of the body, whereby the keys rest horizontally at an acute angle to the inclined 105 plane.

5. A dummy keyboard comprising a body having an upper surface arranged to form an inclined plane, and keys having bodies, of spring metal, provided with inner bent ends 110 brazed to the inclined plane of the body and also provided adjacent to their free ends with shoulders, and looped, character-bearing labels receiving and connected by adhesive to the free ends of the key-bodies and having 115 their ends alined with the shoulders of said bodies.

In testimony whereof I have hereunto set my hand in presence of two subscribing witnesses.

JOSEPH W. McCANN.
